Des. 194,779
Patented Mar. 12, 1963

194,779

EDIBLE SERVING SPOON

James Gordon, 3625 N. Halsted St., Chicago, Ill.

Filed Aug. 20, 1962, Ser. No. 71,380

Term of patent 14 years

(Cl. D8—1)

FIG. 4

FIG. 1

FIG. 3

FIG. 2

FIG. 1 is a front perspective view of an edible serving spoon, showing my new design;

FIG. 2 is a rear elevational view thereof;

FIG. 3 is a side elevational view of FIG. 2; and

FIG. 4 is a cross sectional view taken on a plane passing through the line 4—4 in FIG. 2 and looking in the direction of the arrows.

I claim:

The ornamental design for an edible serving spoon, as shown.
